UNITED STATES PATENT OFFICE.

EDWIN W. SEEGER, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTROMAGNETIC RELAY.

Application filed May 17, 1920. Serial No. 381,853.

- This invention relates to electromagnetic relays responsive to undulating currents.
- In practice there are instances where a relay adapted to respond at a given frequency of current supplied thereto but unresponsive at other frequencies of such current would be extremely advantageous and the present invention has among its objects to provide a simple and reliable relay to so function.
- 10 Another object is to provide a relay which may be readily designed and adjusted to vibrate at a given frequency of current supplied thereto and to be unresponsive at all higher frequencies.
- 15 A further object is to provide an alternating current relay which is adapted to respond only when the current supplied thereto is in a given direction and is at certain frequencies.
- 20 Other objects and advantages of the invention will hereinafter appear.

The accompanying drawing illustrates two embodiments of the invention which will now be described, it being understood that 25 the embodiments illustrated are susceptible of various modifications without departing from the scope of the appended claims.

In the drawing, Figure 1 is a side elevational view of a preferred form of relay 30 embodying the invention, and

Fig. 2 diagrammatically illustrates another embodiment of the invention.

The relay illustrated in Fig. 1 includes a stationary contact 1 and a cooperating contact finger 2 mounted on the armature 3 of an electromagnetic winding 4, said stationary contact and said winding being mounted on the face of an insulating panel 5. The winding 4 has a resistance 6 connected across the terminals thereof and said winding is provided with a magnetic frame 7 having poles 8 and 9, the former carrying the winding 4 and the latter having the contact finger 2 and the armature 3 pivotally mounted thereon. Pole 9 is provided at its forward end with an upwardly curved extension 10 which carries an adjustable stop 11 for limiting outward movement of contact finger 2 and armature 3 under the action of an adjustable spring pressure device 12.

It will thus be observed that energization of winding 4 by an undulating current produces a flux tending to attract armature 3 against the action of spring pressure device 12 for movement of contact finger 2 into engagement with stationary contact 1. Fur-

ther it will be observed that with resistance 6 connected across the terminals of winding 4 the amount of current passing through said winding will vary inversely as the impedance thereof, provided the current in the supply circuit is of constant magnitude. As is well known the impedance of winding 4 varies directly as the frequency of the current supplied thereto, and it is thus apparent that less current passes through said winding at higher frequencies than at lower frequencies. Thus with a given setting of the relay, winding 4 will effect response thereof at given frequencies but will be inoperative to effect response thereof at higher frequencies.

The switch illustrated may be adjusted in various ways for variation of its sensitivity through a wide range. For example, the sensitivity of the relay may be varied by varying the size of the coil 4 and the value of resistance 6; by adjusting the air gap between pole 8 and armature 3 or by adjusting spring pressure device 12.

In some instances it is desirable to provide a relay which is adapted when connected in an alternating current circuit to respond when the instant pulsation of the current in said circuit is in a given direction and at certain frequencies and to remain unresponsive when the instant pulsation of the current in said circuit is in a reverse direction or at other frequencies. The aforescribed relay can be readily modified to function in this manner by providing an additional winding 13 on pole 8 as shown diagrammatically in Fig. 2. The winding 4 is connected in the alternating current circuit while the winding 13 is supplied with direct current. It will thus be observed that winding 13 has a polarizing effect or, in other words, the flux produced thereby assists the flux in winding 4 in closing the relay when the pulsations in said latter winding are in one direction and opposes the flux in said latter winding when said pulsations are in an opposite direction. Thus it is apparent that by properly proportioning windings 13 and 4 the relay will remain unresponsive when the instant pulsation in winding 4 is in a given direction regardless of the frequency of such current. Also since the strength of winding 4 varies with the frequency of the current supplied thereto, assuming that the current in the supply circuit is of substantially constant value

it is apparent that for a given setting of the relay said winding when assisted by winding 13 will effect response of the relay at certain frequencies but will be inoperative 5 to effect response thereof at other frequencies.

While the aforescribed relays are responsive to complete the circuit controlled thereby it is apparent that the same can be 10 designed to break the controlled circuit upon response thereof. Also it is apparent that the movable contact member will vibrate to make and break the controlled circuit if set to respond at relatively low frequencies 15 while the same will remain in its attracted position if set to respond at higher frequencies.

What I claim as new and desire to secure by Letters Patent is:

- 20 1. A relay including an operating winding to be supplied with energy from a source of undulating current of variable frequency but substantially constant magnitude, and means associated with said winding for varying the flux produced thereby upon variations in the frequency of the current supplied thereto to render said relay responsive at given frequencies and unresponsive at other frequencies.
- 25 2. A relay including an operating winding to be supplied with energy from a source of undulating current of variable frequency but substantially constant magnitude and a shunt circuit for said winding including 30 means for varying the flux produced by said winding upon variations in the frequency of the current supplied thereto to render said relay responsive at given frequencies and unresponsive at other frequencies.
- 35 3. A relay including an operating winding to be supplied with energy from a source of undulating current of varying frequency but substantially constant magnitude and a resistance connected across the terminals of 40 said winding to render the same operative to actuate said relay at given frequencies and inoperative to actuate the same at higher frequencies.
- 40 4. A relay including an operating winding to be supplied with energy from a source of undulating current of variable frequency but substantially constant magnitude and means associated with said winding to render the same operative to actuate said relay 45 when the instant pulsation of current supplied thereto is in a given direction and of given frequencies and inoperative to actuate said relay when the instant pulsation of current supplied thereto is in reverse direction 50 or at higher frequencies.
- 50 5. A relay including an operating wind-

ing to be supplied with energy from a source of undulating current of variable frequency but constant magnitude, a direct current winding for rendering said former winding 65 inoperative to actuate said relay when the instant pulsation of current supplied thereto is in a given direction and a resistance connected in shunt to said former winding to render said relay responsive at given 70 frequencies and unresponsive at higher frequencies.

6. The combination with a resistance connected in parallel with the energizing winding of an electroresponsive relay, of a source of alternating current of substantially constant magnitude for said winding, said resistance being adapted to render response of the relay dependent upon subjection of the latter to a given frequency of alternating current.

7. The combination with a resistance connected in parallel with the energizing winding of an electroresponsive relay, of a source of alternating current of substantially constant magnitude for said winding, said resistance being adapted to render response of the relay dependent upon subjection of the latter to a given frequency of alternating current, and means for additionally rendering response of said relay dependent upon the direction of instant pulsation of current supplied thereto.

8. A relay comprising an operating winding to be supplied with energy from a source of alternating current of substantially constant magnitude, and a resistance connected in parallel with said winding whereby said winding when supplied with alternating current of a given value is rendered operative to actuate said relay when the instant pulsation is in a given direction and the current is of given frequencies and whereby the same is rendered inoperative to actuate said relay when the instant pulsation is in a reverse direction or the current is at higher frequencies.

9. A relay comprising an operating winding to be supplied with energy from a source of alternating current of substantially constant magnitude, a direct current winding for rendering said former winding inoperative to actuate said relay when the instant pulsation therein is in a given direction, and a resistance connected in shunt to said first mentioned winding whereby response of said relay is controlled also by the frequency and voltage of the alternating current.

In witness whereof, I have hereunto subscribed my name.

EDWIN W. SEEGER.
